[57] ABSTRACT

The hybrid rectifier includes a structurally parallel arrangement of field effect emitters and collector surfaces. Each respective emitter-collector section may be spaced apart a preselected distance to control the current density in that section. Current density in each section is also a function of the individual emitter pin sizes and geometry. This results in a device which may contain many individual sections having separate and distinct characteristics and thereby providing a multi-function hybrid rectifier.

HYBRID RECTIFIER

DEDICATORY CLAUSE

The invention described herein may be manufactured, used, and licensed by or for the Government for Governmental purposes without payment to us of any royalty thereon.

BACKGROUND OF THE INVENTION

There are presently three types of rectifiers generally in use for electronic applications: gas filled, vacuum, and solid state. The gas filled rectifier is capable of drawing large currents but is limited primarily to lower voltages because the vapor or gas breaks down at higher voltages and arcs. The vacuum rectifier is used for high voltage rectification, it has low current output, is fragile and requires a heated emitter. The heated emitter requires a power source, results in excessive heat, and often requires special cooling. The solid state rectifiers are subject to operational impairment caused by atomic radiation.

The operational impairment of solid state rectifiers is caused by neutrons, electrons, gamma (γ) and x-ray flux. Damage may be transient or permanent depending upon the intensity of the flux and the manner in which the device is being operated. Typically, the damage is defined as displacement damage effect, transient damage effects due to ionization and surface damage effects. Any of these effects can cause total circuit failure under a radiation environment due to open circuit or short circuit conditions, as a result of semiconductor failure. Additional information on this problem area is disclosed in "Radiation Effects in Semiconductor Devices" by Larin, 1968, John Wiley & Sons, Incorporated, New York.

The hybrid rectifier operates on the principle of electric field-effect emission. Electric field-effect emission became possible with the development of a process which produces a material with more than a million per square centimeter metal rods embedded in a metal-oxide surrounding. These rods (fibers or pins) may be formed to protrude from or be recessed in the metal-oxide insulator and they may be etched to various sizes and tip configurations. This metal-oxide matrix material enables electron emission at ambient temperature without the use of any form of emitter heater. The material allows the voltage at which the device operates to be adjusted from approximately 100 volts to hundreds of thousands of volts by variation of emitter size and spacing between the emitter and the collector, which may be accomplished by either adjusting the distance the metal rods are etched into the metal-oxide matrix or by insulating spacers. The metal-oxide matrix is more fully disclosed in U.S. Pat. Nos. 3,745,402 and 3,746,905 and Shelton et al., all co-inventors in the instant invention. U.S. Pat. No. 3,745,402 discloses the unique field-effect electron emitter and U.S. Pat. No. 3,746,905 discloses a high vacuum, field-effect electron tube wherein a field-effect diode is disclosed. A voltage current curve disclosed in these patents sets forth the typical operating voltage range of the device showing the heretofore mentioned lower limit of approximately one hundred volts.

SUMMARY OF THE INVENTION

The hybrid rectifier includes plural emitters which operate at ambient temperatures to emit electrons

without the use of a heated filament and a collector for the emitters. Atomic radiation below thermal destruction levels does not effect the hybrid rectifier since there are no components therein that are destroyed or rendered ineffective by the radiation. Parallel emitter components of various sizes, shapes, and spacing of emitter pins allow the rectifier to have a broad range of usage. The characteristics of each emitter-collector section are selectable to supply the appropriate output. The rectifier is partially or completely encased in a vacuum envelope which may be metal, glass, ceramic or combination thereof.

BRIEF DESCRIPTION OF THE DRAWINGS

15 FIG. 1 is a preferred embodiment, partially in section, of the hybrid rectifier with extraneous structural components omitted.

16 FIG. 2 is a detailed view of an emitter plate with a collector plate on one surface thereof.

20 FIG. 3 discloses a novel application of the hybrid rectifier where different electrical characteristics are employed for supplying power.

25 FIG. 4 is an application of a single hybrid rectifier supplying both rectification and regulation for a load.

26 FIG. 5 is a group of curves showing typical output voltage obtainable for a given half-cycle input voltage.

DESCRIPTION OF THE PREFERRED EMBODIMENT

30 Referring now to the drawings wherein like numbers represent like parts in all figures, FIG. 1 discloses a typical operational configuration of the hybrid rectifier. The hybrid rectifier 10 is a stack of alternately placed collector plates 12 and emitter plates 14. Insulating spacers 16 are disposed between the collector and emitter plates. The collector plates 12 are thin flat sheets of copper or other good conducting metal. For higher power operation these collectors may be temperature controlled by increasing their thickness and passing coolant fluid through spaces provided within them. The partially cut-away view of hybrid rectifier 10, shows typically the spacing between emitters 14 and collectors 12. Emitting fibers 23 are shown protruding from the insulating matrix 24 toward collectors 12. The oxide-matrix emitters are disposed in parallel with the conductive support plates 14a therebetween. By providing different spacing between emitter-collector sections S₁, S₂ etc. and by providing a selectable quantity of emitting fibers 23 per unit area, the various sections of the hybrid rectifier may have separate or identical characteristics, depending on the operational requirements for each section. Insulation spacer 16 may be disposed between emitters 14 and collectors 12 and may be completely around the periphery of each emitter collector section S₁, S₂, etc. for handling or insulation purposes as required.

35 A more detailed view of emitting plate 14 is shown in FIG. 2, the emitting plates 14 consisting of a center conductor sheet 20 with the emitting matrix 22 brazed, soldered or by some other acceptable means electrically fastened to the center conductor. The center conductor 20 is shown slightly larger than the emitting material 22 electrically bonded to it. This allows for ease of handling and placement of electrical insulation if the emitting fibers 23 protrude from the surface 24 of the matrix. If the fibers are etched below surface 24 of matrix 22, collector 12 may be joined to the matrix sur-

face. Typical electrical connections of copper collectors 12 are shown as lead-in conductors 26A and 26B and electrical connections for emitter plates 14 are made to electrical conductors 28A and 28B.

The hybrid rectifier is connected into an electrical circuit in the same manner as other types of rectifiers. An electric potential is applied across the rectifier from a voltage source, an electric field is generated in the region between the collector and the emitting oxide-metal matrix of each section. Since the matrix consists of a collection of ultra-fine conductors separated by an insulating, supporting structure, the electric field concentrates at the points of the ultra-fine conductors. These conductors in this material are sufficiently fine for electrons to be emitted from their points. The electrons flow to the collector plate giving a current in the circuit. The amount of current depends on the strength of the electric field, conductor diameter, and number of conductors per unit area in the matrix material. These parameters are adjusted along with total emitter and collector area for individual applications. The entire device is encased in a vacuum envelope for operation. Extreme structural rigidity may be obtained by pinning the stack together with electrically insulated bolts and shrinking a glass or ceramic envelope on the whole structure.

The rectifier differs from state of the art solid state rectifiers in that the back voltages leakage current is zero and it is not subject to atomic radiation degradation at below thermal destruction levels. These features plus its rigid construction allows better instrumentation in high flux density applications. Also since there is no back voltage leakage current, no protective resistors are required in the circuitry thereby reducing components and simplifying design.

The electrical characteristics and the simple design of the hybrid device make it possible to use it for a number of unique applications. Since the current density through each section is a function of the individual emitting pin size and geometry as well as the spacing between emitter and collector, the characteristics of each section can be specified. This results in a device which can contain many individual sections with each section having distinct characteristics. A novel application results when sections with different electrical characteristics are used as rectifiers for several power supplies as shown in FIG. 3. In this application the characteristics of each emitter and collector section are selected to supply the appropriate output, and the collectors are connected in parallel to one side of a transformer T. After conventional components such as filter 30 is added, the hybrid device is capable of supplying a relatively consistent potential under varying load conditions when used as a voltage rectifier. In FIG. 3, the transformer T supplies the same alternating voltages to all sections represented by S₁, S₂ through S_n. The output voltage from respective sections V₁ through V_n depends on the loads L₁ through L_n plus the emitter-collector characteristics of each section of the rectifier.

A second application is in a regulated power supply in which one or more sections (S₁) are used for rectification and one or more of the other sections (S₂) are used for regulation, since the electrical characteristics are such that they can be used for parallel voltage regulation. This circuit is shown in FIG. 4 wherein section S₁ of the hybrid device is connected in the conventional manner and supplies the voltage to load L. A series re-

sistor R is placed in the circuit primarily for transformer protection, to supply a small degree of regulation, and to work in conjunction with the regulating section S₂. The load L does not draw a uniform current flow, but varies as the load varies over an extended range of values. During operation, as the current requirements decrease less of the supply voltage is dropped across resistor R and the voltage tends to increase which results in increased current flow through S₂ which in turn increases the current through resistor R, decreasing the voltage to the specified value across the load.

A third novel application consists of using several sections of the hybrid rectifier in parallel to shape the output current curve for special applications requiring specific rise times. In this application, the various sections have slightly different electrical characteristics, as may be obtained by emitter-collector spacing and packing density of emitting fibers. This electrical, parallel hybrid rectifier circuit may be obtained as shown in FIG. 1, by merely coupling selected sections to output leads 26-28. The resultant output typical of this application is shown in FIG. 5. As indicated in FIG. 5, the output currents from three respective sections S₁, S₂ and S₃, when arranged in parallel, are O₁, O₂, and O₃ which combine to give the resultant output O_T. The shape of O_T is determined by the design of the hybrid device and can be changed over a wide range.

Although a particular embodiment and form of the invention has been described, it will be appreciated by those skilled in the art that modifications may be made without departing from the scope and spirit of the invention. Accordingly, it is understood that the invention is limited only by the claims appended hereto.

We claim:

1. A hybrid rectifier comprising: plural parallel collector plates, plural parallel electron emitter plates disposed respectively between said plural collector plates and parallel therewith, voltage means coupled to respective of said emitter and collector plates for coupling a potential thereacross and thereby developing an electric field therebetween, said emitter plates having first and second emitting surfaces for conducting electrons simultaneously from opposing faces thereof toward respective first and second collectors in response to an electric field developed therebetween, each of said emitter plates comprise a conductive sheet sandwiched between said emitting surfaces for electrically coupling said potential thereto, and each of said emitting surfaces comprises a field-effect electron emitter having a plurality of uniformly spaced parallel emitting pins disposed normal to said conductive sheet and an oxide metal insulator disposed between adjacent pins for insulating, encompassing, and supporting said pins.

2. A hybrid rectifier as set forth in claim 1 wherein respective collector plates are spatially disposed separate and distinct distances from emitting surfaces of said emitter plates for operating in electric fields of differing strengths.

3. A hybrid rectifier as set forth in claim 1 wherein said emitting pins are terminated below the insulating oxide metal surface and respective collector plates are disposed on the surface of said oxide metal insulator.

4. A hybrid rectifier as set forth in claim 1 wherein each of said field-effect electron emitter surfaces have different emitting pin density per unit area with respect to other emitter surfaces providing selectable voltage

ranges of field-effect emission, said emitting pins having a minimum density of one million emitting pins per square centimeter of surface area.

5. A hybrid rectifier as set forth in claim 4 wherein insulator spacers are disposed between adjacent emitter and collector plates for providing selected spatial separation therebetween to control field-effect emis-

sion.

6. A hybrid rectifier as set forth in claim 1 wherein insulator spacers are disposed between adjacent emitter and collector plates for providing selected separation therebetween to control field-effect emission.
